UNITED STATES PATENT OFFICE.

HUGO W. H. BETH, OF WORCESTER, MASSACHUSETTS, ASSIGNOR TO NORTON COMPANY, OF WORCESTER, MASSACHUSETTS, A CORPORATION OF MASSACHUSETTS.

TUNNEL KILN.

Application filed December 15, 1920, Serial No. 430,876. Renewed January 7, 1924.

To all whom it may concern:

Be it known that I, HUGO W. H. BETH, a citizen of the United States of America, residing at Worcester, in the county of 5 Worcester and State of Massachusetts, have invented certain new and useful Improvements in Tunnel Kilns, of which the following is a full, clear, and exact specification.

10 My invention relates to tunnel kilns and more particularly to a kiln and kiln car construction providing for a turntable, mounted on the car, which may be rotated during the passage of the car through the tunnel 15 kiln.

In the firing of ceramic ware or other articles which require a high temperature heat treatment, it is important that all parts of the article be brought up to the maximum 20 temperature at the same rate. This is difficult to accomplish in tunnel kilns by the use of kiln cars such as those which have been used in the past, due to one or more of various factors which cause an uneven distribution throughout the cross section of the 25 heating chamber.

Likewise if the charge of ware becomes unevenly heated, convection currents of air may be set up through the heating part and 30 serve to equalize the temperature throughout. But in either case, the radiated heat from the combustion chamber or whatever may be the source of heat will act only upon that side of the ware which is nearest 35 to it, and conduction or convection or both together will not entirely make up for the concentration of its heat effect upon the ware.

It is accordingly an object of my invention 40 to overcome the difficulties which have been experienced in the firing of ware which requires a uniform heat treatment and to provide a tunnel kiln construction in which this will be accomplished by causing the 45 ware to travel through the kiln upon trucks and rotating the ware during its passage through the kiln, and to thus improve the quality of the product.

The accompanying drawings illustrate 50 one embodiment of my invention in which:

Figure 1 is a plan view of a kiln car;

Fig. 2 is a longitudinal elevation, partly in cross section, of a kiln car, the tracks and rack bar hereinafter described; and

55 Fig. 3 is a transverse cross section of a

tunnel kiln partly broken away, showing an end elevation of a kiln car in place upon the tracks.

In accordance with my invention, I provide a tunnel kiln construction comprising 60 a car for conveying ceramic or other ware through the kiln which has a rotatable turntable upon which the ware may be loaded, and I provide suitable mechanism for rotating the turntable while the car is within 65 the kiln.

If it is desired that the turntable be uniformly rotated as it passes through the kiln, it may be operated and controlled by the mechanism ordinarily employed to push 70 such cars through the kiln, as for example by connecting a gearing on the turntable with cooperating parts fixed upon the kiln wall.

In the embodiment of my invention illustrated in the drawings and which is herein-after described, I may employ a tunnel kiln 75 10 provided with parallel longitudinal walls 11 at the sides, and between them a floor 12 whereon are laid the tracks 13. Any method 80 of heating the kiln may be employed, though in the present construction I have shown a kiln of the Dressler type having the muffles 14 and heating flues 15.

The kiln car 20, considered as a whole, is 85 rectangular in shape and comprises a metallic platform or frame work 21 suitably mounted on the wheels 22, which in turn rest upon the tracks 13 already mentioned. The turntables 24, the number of which depend 90 upon the size and shape of the car, are circular in cross section and may be built of refractory blocks 25 and 26 of desired shapes which are shown as forming a cylindrical space 27 in the center which may be 95 filled with any refractory insulating material such as magnesia. The cylindrical section formed by the blocks 25 and the super-imposed conical section formed by the blocks 26 are held in place, and the blocks 100 in each section are held together, as by a metallic band 28. The top of each turntable 30 may be constructed of a highly refractory material, such as bonded fused alumina, to withstand the temperatures which are to 105 be employed.

In order to rotate this massive body, the upper portion of each of the turntables thus constructed may be fastened to and supported by a metallic plate 33 having an annular 110

ball race 34 which rests upon bearings 35 in a similar ball race 36 which is fastened to the car platform 21. The metallic supporting plate 33 is fastened to a central shaft 37 which is suitably mounted in bearings in the car platform 21. A bevel gear 38 fixed on the lower end of shaft 37 meshes with a similar gear 40 on one end of the horizontal shaft 41 which is supported in bearings suspended below the car platform. The shaft 41 has another bevel gear 42 on its opposite end. The gear 42 of each turntable is so located as to mesh with the single bevel gear 44 which is mounted upon the transverse shaft 45 supported by a bearing yoke 46, between the forks of which is a gear wheel 47. The rack bar or cog rail 49, which is shown as fastened to the bottom of the kiln, runs throughout the desired portion of the kiln and meshes with the gear wheel 47 on the shaft 45 so that as the car is pushed through the kiln along the tracks, as is the customary practice, the wheel 47 is rotated, which, through the gearing already described, causes the turntable to rotate at a speed proportionate to the rate of passage of the car through the kiln. The outer end of the shaft 45 has a squared-off portion 51 to which a crank may be applied for rotating the turntables manually.

The rectangular shape of the car is built around the turntables 24, and made level with or slightly lower than the turntable tops, of the special refractory blocks 29, care being taken that they will not interfere with the free passage of the car through the kiln and other moving parts, nor with the rotation of the turntables.

In the operation of my invention, therefore, the ware to be burned is loaded upon the turntables 24 of the kiln car in suitable containers, care being taken that no part of the load projects beyond their circumferences and that it be so stacked that there will be no displacement of it during its passage through the kiln. The gear wheel 47 is then rotated by means of a crank applied to the shaft end 51 so that it will properly engage the teeth of the rack bar or cogged rail 49. The car is then pushed into the kiln, this usually being done automatically and comparatively slowly so that the car and the ware piled upon it will not be unnecessarily disturbed. By this forward movement of the car the gear wheel 47 is made to rotate by its engagement with the stationary rack bar 49 and in turn rotates the shaft 41 which rotates the turntables 24. Accordingly the ware is rotated as it passes along the length of the kiln and uniformly subjected to the heat which is directed upon it by radiation as well as by conduction and convection currents of the heated air. As a result, all parts of the charge are uniformly heated, which develops a greater uniformity of structure,

quality and appearance in the product which has been fired in this manner. Consequently, the amount of material which it is necessary to reject is appreciably decreased, thus making a considerable saving in the cost of ultimate manufacture.

Having thus described my invention, what I claim as new and desire to secure by Letters Patent is:

1. A tunnel kiln comprising a movable kiln car platform, a refractory turntable mounted thereon to rotate in a horizontal plane, a plane-surfaced layer of super refractory material on said table to support the ware, a refractory superstructure supported upon said movable platform partially surrounding said turntable at the sides to form a car body having a substantially solid top, and means for rotating the turntable while the car is within the tunnel 85 kiln.

2. A tunnel kiln comprising a movable kiln car platform, a refractory turntable rotatably mounted thereon to support the ware to be fired upon its upper part, the lower part of said turntable being constricted to a shorter diameter, a refractory superstructure supported upon said movable platform and surrounding the lower portion of the turntable to provide a car body of substantially rectangular cross section, and means for rotating the turntable during the passage of the car through the tunnel kiln.

3. In a tunnel kiln, the combination of parallel longitudinal kiln walls providing a passage therebetween through the heating chamber of said kiln, and a kiln car adapted to convey the ware to be fired through said passage, said car having a refractory turntable mounted thereon to rotate in a horizontal plane, and means comprising cooperating members on the car and on a kiln wall for rotating the turntable during the passage of the car through the kiln.

4. The combination in a tunnel kiln having longitudinal walls, of a kiln car for conveying the ware to be fired through such a kiln, comprising a movable platform, a refractory turntable for supporting the ware mounted thereon to rotate in a horizontal plane, a refractory superstructure cooperating with said turntable to form a rectangular car body, and means for rotating said turntable during its passage through the kiln comprising gearing connected with the turntable and a member on a kiln wall cooperating with said gearing.

5. The combination in a tunnel kiln having walls and a longitudinal passageway therebetween for a kiln car, of an extensive rack bar fixed on a wall of said kiln and a kiln car for conveying the ware to be fired through said passageway, said car be-

ing provided with a turntable mounted to rotate in a horizontal plane, and means including gears connected with the turntable and engaging said rack bar to rotate the 5 turntable during its passage through the kiln.

6. The combination in a tunnel kiln having a longitudinal wall, of a kiln car for conveying the ware, comprising a movable 10 platform, turntable plates on said platform,

bearing supports permitting rotation of said plates, refractory superstructures on said plates adapted to support the ware to be fired, and gear mechanism comprising a rack bar on a kiln wall for rotating the 15 turntables simultaneously as the car moves through the kiln.

Signed at Worcester, Massachusetts, this 11th day of Dec., 1920.

HUGO W. H. BETH.
